UNITED STATES PATENT OFFICE.

HARRISON H. EATON, OF CLEVELAND, OHIO.

DESIGN FOR A LACING-HOOK FOR GLOVES.

SPECIFICATION forming part of Design No. 27,931, dated December 7, 1897.

Application filed October 11, 1897. Serial No. 654,892. Term of patent 14 years.

To all whom it may concern:

Be it known that I, HARRISON H. EATON, a citizen of the United States, residing at Cleveland, in the county of Cuyahoga and State of Ohio, have invented and produced a new and original Design in Lacing-Hooks for Gloves and Shoes, of which the following is a specification, reference being had to the accompanying drawings, forming part thereof.

10 Figure 1 is a plan view of my new and original design in lacing-hooks. Fig. 2 is a side elevation thereof, looking in from line 2 2, Fig. 1. Fig. 3 is a side elevation looking from line 3 3, Figs. 1 and 2. Fig. 4 is a side elevation looking from line 4 4, Figs. 1 and 2. Fig. 5 is a side elevation looking from line 5 5, Fig. 4.

15 The leading feature of my design consists in the shape or formation of the hook as shown in the foregoing views.

In its entirety the design comprises the three features of a tubular shank *a*, a head *b*, and a hook *c*. The base of the head *b* is flat, while out of its top and somewhat off its center starts the hook *c*. This hook is peculiar in its relation and shape, rising out of the head *b* somewhat off the center and ex-

tending upward and thence laterally on compound curvatures, after the fashion of a horn. In this novel curvature several distinct individual curves are especially noticeable: first, the curve in plan, Fig. 1, between points *e* and *e* and defining substantially a segment of a perfect circle; secondly, the curvature between the points *g* and *g*, Fig. 2, 35 which likewise corresponds substantially to the segment of a perfect circle; thirdly, the upwardly-curved recess *h* in the neck of the curved portion *g* and *g* on its under side, Fig. 2, and, lastly, the noticeable upward curvature of the extremity of the horn, as clearly seen in Figs. 2 and 5. The base of the horn is further characterized by a fullness at *k* on its under side.

What I claim is—

45 The design for a lacing-hook, substantially as shown and described.

Witness my hand to the foregoing specification this 6th day of October, 1897.

HARRISON H. EATON.
